James MacGregor Jr.

UNITED STATES PATENT OFFICE.

JAMES MACGREGOR, JR., OF TROY, NEW YORK.

COOKING STOVE AND RANGE.

Specification of Letters Patent No. 11,673, dated September 12, 1854.

To all whom it may concern:

Be it known that I, JAMES MACGREGOR, Jr., of the city of New York, (late of the city of Troy,) in the State of New York, 5 have invented new and useful Improvements in the mode of constructing ranges, cooking stoves, and such like articles, whereby baking is greatly facilitated, and with more certainty and economy; and I 10 do hereby declare that the following is a full, clear, and exact description thereof, reference being had to the accompanying drawings and the letters of reference marked thereon.

15 The same letters indicate like parts in all the drawings.

The nature of my invention consists—

First. In having the area of the fire plates (forming the fire box or pot) larger 20 than usual, so that at all times, there may be sufficient heat passing through the plates of the firebox to operate the ovens, with the smallest amount of combustion of fuel that will satisfactorily do the boiling—which is 25 usually done by my improved articles—when nearly all the draft of the chimney is cut off from the fire. The plates of the firebox or pot are plates not connected with the permanent part of the range or stove 30 any more than is necessary to keep them in their places and are so formed that they are readily taken out and replaced, but as this is common with all stoves having iron fire plates or pots, a minute detail is not 35 deemed profitable or requisite.

Second. In having a flue or flues surrounding the oven or ovens (or partially so and then reverting) the air in which is heated by the heat that passes through the 40 plates of the fire box or mostly so. These flues are intended to be air tight, so as to prevent the air from escaping from the flues and to prevent ashes from falling into the flues. (In some instances the air is 45 made to pass into the oven and act directly on the things to be baked and by a flue on the farther side of the oven return to the fire pot or plates.) The air in these flues in those parts between the firebox and the 50 oven is more heated and of course lighter, and from being lighter, rises and the air in the flues farthest from the firebox, being

heavier, descends and thus a constant and rapid circulation of hot air is made to pass around or partially around the oven or 55 ovens in these flues—from which the oven or ovens, receive their required, or nearly their required heat. To prevent that part of the oven, nearest the firebox, from being over heated—I put one or more plates in 60 the flue between the firebox and the oven, thus dividing the flues in that part into two or more flues—and the same on top—if it be too hot—or any nonconducting substance may be used to equalize the heat. 65

Figure 1, represents a bird's-eye view. A, represents the top of the range with all the covers off and the grate removed, from the firebox. B, represents the water-back. B' B', represents the water pipes. C, C, 70 represents the bars on which the grate rests. D, D, represents the smoke pipes. E, E, represents the two covers, that are to be removed, when the draft is to be lessened. F, F, F, F, F, represents the boiler-holes. 75 G, G, represents the plates, that cause the draft, to go forward to the covers E, E, before it can reach the smoke flues.

Fig. 2, represents an elevation taken at the line N. B, represents the water-back. 80 B', B', represents the water pipes. C, represents the back bar on which the grate rests. D, D, represents the smoke pipes. G, G, represents the plates, that divert the drafts, as above stated, in front of the 85 covers E, E. L L L L L L represents the flues that surround the ovens, in which the hot air circulates around the ovens and communicates the required heat to the ovens. I, represents the fire box or chamber of 90 combustion. K, K, represents the ovens. A, represents the top of the range. F, represents the center piece, supported by the pedestal O. M, M, represents the plates that divide the flues between the ovens and 95 the fire box. O, represents the pedestal, that rests on the water back and rises to the bottom of the center piece and prevents it from deflection.

Apertures may be made, into the flues 100 surrounding or partly surrounding the ovens, to let in cold air, and to let out the hot air, to regulate the heat in the ovens or to heat any other space—when not required

for baking—also to clean out any sediment, that may lodge in the flues. The fire is kindled and the range operated, the same as other articles—for like purposes, excepting 5 with less draft. The firebox is, generally, to be kept about full of coal and is not generally allowed to go out at night.

Having thus fully described the nature of my invention and the mode of operating the

same, what I claim as my invention and 10 desire to secure by Letters Patent, is—

Having a flue or flues surrounding the oven or ovens, for the purpose, and in the manner, substantially as above set forth.

JAMES MACGREGOR, JR.
